UNITED STATES PATENT OFFICE.

OLOF N. TEVANDER, OF CHICAGO, ILLINOIS, ASSIGNOR TO STANDARD CAP & SEAL CORPORATION, OF CHICAGO, ILLINOIS, A CORPORATION OF VIRGINIA.

CLOSURE-APPLYING MACHINE.

Application filed July 21, 1926. Serial No. 123,936.

My invention relates to machines or tools for twisting together the ends of a loop made of a strand of string or other material so that the loop ends will remain in assembly. If the string of which the loop is formed is non-metallic, the twisted ends may be held in assembly by some suitable agency such as sealing wax. If the string is of metal, it is commonly called wire and 10 the twisted ends thereof will remain in assembly without the aid of any additional means. I prefer to employ metallic wire for the sake of simplicity in the manner of its treatment but the invention is not to be thus limited, nor is it to be limited to the 15 use of strands that are circular in cross section.

The tool or machine of my invention has been designed particularly for use in fastening the skirts of caps about the necks of 20 bottles, such as milk bottles, having circumscribing beads at their mouths. In such use of the tool of my invention, the loop of the string is disposed to have its plane 25 angular to the axis of the neck of the bottle on the bottle positioner, the loop being in alinement with the bottle neck, the mechanism for forming the loop and bottle positioner being relatively adjustable to enable 30 the location of the loop about the skirted closure cap after which mechanism operates to twist the loop ends together to form the loop into a ring and to contract the ring about the skirt of the cap. The ends of the 35 loop are preferably grasped by two grippers or holders, one for each loop end, and preferably both grippers or holders are thereafter revolved to twist the ends of the loop together to bring the loop into the form 40 of a circle completely surrounding the bottle neck, the action of the machine being such as to tightly draw the looped strand of wire or string about the cap skirt to bring the cap skirt into very intimate contact with 45 the bottle neck in the zone of the loop, the bead about the bottle mouth coacting with the tightened loop to prevent the withdrawal of the cap.

In the preferred embodiment of the invention, the grippers or holders are provided upon arms which are adapted to be crossed but which are initially uncrossed so that the bight of the loop may be initially drawn tightly against one side of the cap

whereafter the arms are crossed to cross the 55 ends of the loop, the arms being together revolved after the ends of the loop are crossed to twist the loop ends together. If the string is non-metallic, cement, such as sealing wax, is applied to the ends of the loop, 60 where twisted, to maintain the twist. If the string is metallic, the twisting will remain without the addition of cement.

I have herein disclosed a bottle capping machine employing metallic wire for binding the skirts of closure caps about the necks of bottles. In the machine, as I have preferably designed it, there is included a guide which shapes a strand of such wire into a loop whose sides are spaced apart a 70 distance greater than the diameter of the cap skirt; the grippers or holders being arranged to grasp the ends of the wire loop. Mechanism is employed for pulling upon the arms that carry the grippers or holders 75 in a direction to apply the bight of the loop to one side of the cap skirt whereafter said arms are crossed and are together rotated to effect the twisting. In the preferred embodiment of the invention, the wire is fed 80 from a reel and is severed after the initial formation of the loop so that both ends of the loop are free to be readily twisted. Mechanism is employed having elements 85 operated in orderly sequence for automatically positioning the bottles to receive the loops, to feed the wire to initially form the loops, to draw the initially formed loops against sides of the bottle caps, to sever the wire into loop lengths to cross the arms carrying grippers or holders, and to rotate the crossed arms to twist the wire.

The invention will be more fully explained in connection with the accompanying drawings illustrating the preferred embodiment 90 thereof as employed in a milk bottle capping machine and in which Fig. 1 is a view mainly in elevation of a milk bottle capping machine containing the preferred form of my invention, some parts being shown in 100 section; Fig. 2 is a sectional view on line 2-2 of Fig. 1; Fig. 3 is a view generally taken on line 3-3 of Fig. 1 but also somewhat diagrammatic; Fig. 4 is a sectional view on line 4-4 of Fig. 2 but showing additional mechanism not appearing in Fig. 2 and with some of the parts omitted; Fig. 5 is a sectional view on line 5-5 of Fig. 4,

the sequence of operations being noted upon this figure; Fig. 6 is a perspective view illustrating one of the two grippers which are similarly formed with a portion of the arm carrying this gripper; Fig. 7 is a sectional view on line 7—7 of Fig. 8; Fig. 8 is a sectional view on line 8—8 of Fig. 5 and also on line 8—8 of Fig. 7; Fig. 9 is a view showing a portion of the mechanism that appears in Fig. 7 with parts in changed positions but before the completion of the wire twisting operation; Fig. 10 is a view showing some of the parts appearing in Fig. 9 after the twisting operation has been completed; Fig. 11 is a view showing the mechanism portion illustrated in Fig. 9 and additional parts, this figure illustrating the grippers in their initial positions preparatory to the twisting operation; Fig. 12 is a view on line 12—12 of Fig. 8; Fig. 13 is a view on line 13—13 of Fig. 8; Fig. 14 is a perspective view illustrating a cap fastener in place by a metallic wire ring formed of a looped strand of wire whose ends are twisted by the operation of the machine; and Fig. 15 illustrates the application of the skirt of a bottle cap to a bottle neck by means of a non-metallic string operated upon by the machine and whose twisted ends are maintained together by means of a bead of sealing wax or other cementitious material.

The bottles 1 are suitably supplied to a stationary deck 2 carried upon posts 3 which are supported by the base 4 of the machine. These bottles have caps 5 initially loosely applied thereto, these caps being desirably constructed as disclosed in United States Patent 1,117,147, dated November 10, 1914. The skirts of these caps are to be tightened about the bottle necks by the machine of my invention so as to underlie the beads 6 about the bottle mouths shown by dotted lines in Fig. 1 and in the broken illustration of the bottle appearing in Fig. 8. The bottles, with the loose caps thereon, are fed through the chute 7 in position to be engaged by the teeth of the star wheel 8 which serve to continue the travel of the bottles as they leave the chute and to direct the same individually onto the vertically adjustable sections 9 of a disc-like table 10, these table sections constituting bottle positioners.

Any suitable mechanism may be employed for operating the various operating elements that are located above the deck 2. In the embodiment of the invention illustrated, an electric motor 11 may be employed for operating a main drive shaft 12. Power is transmitted to this drive shaft at adjustable speed through the intermediation of any suitable speed changing gearing 13. The shaft 12 has a worm 14 thereon which is in mesh with a worm wheel 15. This worm wheel is fixed upon a shaft 16 on which there are also fixed the spur gear 17 and the table 10. This spur

gear is in mesh with another spur gear 18 that is fixed upon a shaft 19 upon which shaft is also fixed the star wheel 8.

The bottle supporting table 10 is constantly turned and while turning, the sections 9 thereof are gradually elevated from the plane, proper, of the table and gradually restored to this plane, the final capping operation that is to be described occurring when said table sections are in their upper limits of their movements.

I provide a stationary cam track 20 upon which cam rollers 21 travel, to rise and fall. Each table section 9 is assembled with a cam roller so as to rise and fall therewith. As illustrated, each table section 9 is carried at the upper end of a spring barrel 22. A piston 23 is within the lower end of the spring barrel and is normally held in fixed relation therewith by means of a spring 24 which abuts at its lower end upon the piston and at its upper end against the top end wall of the spring barrel. A link 25 connects each piston 23 with one end of a bell crank 26 upon whose elbow the corresponding cam roller is journaled. The other end of this bell crank is pivoted upon an arm 27 depending from a bearing support 28 which is fixed upon the shaft 16 and is located below the table 10.

As the shaft 16 turns, the cam rollers move bodily therewith over the cam track 20 to elevate and lower the table sections 9 to enable these table sections to function. As the shaft 16 and the parts thereon turn, the spring barrels 22 rise and fall due to the normally fixed relation of the pistons 23 therewith. These spring barrels are guided in their movement by bearings 29 in the bearing support 28. If, in the final capping operation, the bottles should encounter undue strain, the springs 24 will yield to prevent the bottles from breaking, the pistons 23 then rising in the spring barrels.

A support 30 is in normally fixed relation with the shaft 16. This support has splined connection with the shaft 16 as indicated at 31 whereby it may be permitted movement lengthwise of the shaft. A large split nut 32 is screwed upon the upper end of the shaft 16 and has tongue and groove connection with the support 30 so that this support may be elevated and lowered along the shaft. A hand wheel 33 is provided upon the nut 32 to facilitate the turning thereof. The support 30 carries the balance of the mechanism that is complementary to the table sections 9 and the mechanism for fastening the caps upon the bottles. The support 30 is circular and concentric with the shaft 16. The periphery of this support is closely received between rollers 34 that project laterally from the sleeves 35, whereby these sleeves are assembled with and are carried by said support. These sleeves are adapted to

slide upon the upright guide rods 36. These guide rods carry the spider 37 at their upper ends, this spider carrying the sleeve bearing 38 for the upper end of the shaft 16.

5 Yokes 39 are bolted to the upper side of the support 30, each table section 9 having a yoke individual thereto and located immediately above the same to be in line therewith. Each yoke straddles an opening 40 in line with the corresponding table section 9, this opening being sufficiently large to permit of the free passage of the bottle neck therethrough. Each yoke carries a chuck 41 also constituting a bottle positioner and 15 which is in the form of a shell in line with the corresponding underlying table section 9. The chucks are somewhat in the shape of bells that are flared at their lower ends and which are slotted at their lower ends to be 20 spring-like. When the table sections 9 are elevated to a predetermined extent, the mouth ends of the bottles and the caps thereon are snugly received in the chucks so that the bottles and their caps are properly centered with respect to the wire or string applying mechanism of my invention. Each yoke carries a horse-shoe or looped shaped guide 42 formed with a wire receiving groove 43, the spaces within these guides being 25 aligned with the corresponding chucks 41 and table sections 9. The loop shaped guide 42 is in alignment with the underlying bottle supporting table section when this table section is brought to rest to have the closure 30 cap secured to the mouth of the bottle on this table section. Each chuck 41 and guide 42 is in association with the wire shaping and applying mechanism of my invention, there being one such mechanism individual 35 to each such chuck and guide, numerals applied to each such mechanism being similarly applied to other of such mechanisms. Each wire applying mechanism, in addition to the guide 42, also employs two holders 40 preferably in the form of grippers constructed as illustrated in Fig. 6. Each gripper is inclusive of a jaw 44 integrally formed with a gripper supporting arm 45 and a jaw 46 complementary to the jaw 44 and pivotally connected therewith by the pin 47. The jaw 45 of each gripper is formed with a cylindrical opening 48 through the front half thereof. The strand of wire 49 which is fed from the reel 50 and is threaded through 50 the openings 48 is received in the corresponding groove 43 to form a loop which is initially U-shaped as shown in Fig. 7. When the strand of wire has received this initially U-shaped loop, it is severed by the 55 knife 51 to make the loop of desired length and to give the loop its second free end, it being preferable to have two free ends upon the loop before exercising the twisting operation thereon. The wire cutting operation 60 will be later more fully set forth. The loop

which is formed in the strand is in a plane which is angular to the axis of the neck of the bottle on the positioner in order to receive said bottle neck when the positioner and loop forming mechanism have been suitably relatively adjusted along the bottle axis. After the loop has been severed, the ends thereof are twisted together, by mechanism which will be described, to form the loop into a ring and to contract the ring 75 about the skirt of the cap.

After the wire cutting operation, the gripper or holder supporting arms 45 are moved from the initial positions shown in Fig. 7 to their crossed relation shown in Fig. 9 in which operation the jaws 46 are turned by the wire from their positions shown in Fig. 7 to the positions thereof shown in Figs. 9 and 10 whereby the ends of the wire loops are gripped. To ensure the hold of the 85 grippers upon the ends of the wire loop, these loop ends are bent as indicated at 52. The bending of the wire is caused by the shoes 53, 54 which are carried upon the support 30 the shoe 53 being carried by and 90 integrally formed with the wire guide 55 that directs the wire from the corresponding reel 50, while the shoe 54 is carried by the corresponding yoke 39. The gripper arms, in being crossed, tightly encircle the wire 95 loop about the corresponding bottle cap, the bends at 52 in the wire preventing the wire from being withdrawn from the grippers. After the gripper arms have been crossed to cross the sides of the loop as indicated in 100 Fig. 9, the gripper arms are turned to twist the wire as indicated in Fig. 10, the gripper arms being turned, say, to twist the wire twice, as indicated in Fig. 10. After the wire has been twisted as indicated in Fig. 10, the rotation of the gripper arms is stopped 105 whereafter they are uncrossed, as indicated in Fig. 11. In this uncrossing operation, the twisting of the wire loses one-half of a turn and the bends at 52 are somewhat straightened. When the gripper arms are uncrossed, the jaws 46 are brought into their initial adjustment to permit of the passage of the wire therethrough, Figs. 7 and 11, by means of the stops 56 carried by the yoke 39.

110 The mechanism for operating the grippers and the knife 51 and the mechanism for feeding the wire will now be described. Each cycle of operations commences with the bottle that is placed upon the table section 9 by the star wheel 8, that is, each cycle of operations commences with the bottle that is in the extreme left hand position with the table section 9, that supports the bottle, in its lowermost position. The table 10, together with its movable sections 9, and the support 30 are rotated together constantly and at a uniform rate. During the first portion of the turning movement of said table and support, about one-eighth of a revolu- 115 120 125 130

tion, the table section 9 which supports the left hand bottle is raised by the cam track 20. During the next one-eighth of the revolution of said table and support, the 5 wire is caused to be fed from the reel 50 that is individual to said raised table section 9. Each mechanism for feeding wire is inclusive of grooved wire feeding discs 57 and 58 turning in the same plane with the wire 10 grooves thereof matching to receive the wire together, meshing spur gears 59 and 60 respectively fixed upon and coaxial with said discs, a shaft 61 carrying the disc 58 and spur gear 60, a bevel pinion 62 fixed upon 15 the shaft 61, a bevel pinion 63 meshing with the pinion 62, a mutilated spur pinion 64 fixed upon the shaft that carries the pinion 63, and the stationary arcuate gear segment or rack 65 carried by the normally stationary gear carrier 66, this gear carrier being carried by the sleeves 35 so that it may be adjusted, together with the support 30, to suit the height of bottles being operated upon. A bracket 67 carries the shafts upon 20 which the elements 58 to 64 inclusive, of each wire feeding mechanism, are respectively fixed. A disc 68 is fixed upon and is coaxial with each mutilated pinion 64. The pinions 64 and rack 65 are in one zone and the discs 30 68 are in another zone. Each disc 68 has a flattened edge portion 68' which is engageable with a normally stationary segmental track 69 in the same zone therewith, the track 69 and rack 65 being coaxial. During 35 the rotation of the support 30 and table 10, the mutilated pinions 64 are brought into mesh with the rack 65, this meshing occurring during the second one-eighth revolution of said support and table. During this one-eighth of a revolution, the wire feeding discs 57 and 58 are turned to feed the wire through the guide 55 a length corresponding to the length of the loop of wire that is to be wrapped about a bottle neck. At the conclusion 40 of this one-eighth of a revolution, the flattened side of the corresponding disc 68 is brought into engagement with the arcuate track 69 to prevent further rotation of the corresponding pinion 64 so that the corresponding wire feeding mechanism will be arrested from further feeding operation until the next cycle of operations. After 45 the wire has been thus fed, the knife 51 is operated to shear the wire, this operation occurring during a few degrees of the succeeding turning movement of the table 10 and support 30. The knife 51 is carried by one end of the bell crank lever 70 which is pivoted at its elbow upon the bracket 71. The other end of the bell crank carries a 50 roller 77. A spring 73 presses the bell crank in a counter-clockwise direction, Fig. 12, to an extent which is limited by the engagement of the lug 74 on the bell crank with the bracket 71. The various rollers 72 upon the

various bell cranks 70 are normally positioned to be in the same zone by the various springs 73. A single cam post 75, common to all the rollers 72, is stationarily mounted upon the stationary gear carrier 66 and extends into the normal zone of the rollers 72 to an extent to depress the roller presented thereto sufficiently to move the corresponding knife 51 in a wire shearing direction. After the post 75 has been passed, the corresponding spring 73 restores the corresponding knife to normal position.

During the next few degrees of the turning movement of the table 10 and support 30, the gripper arms 45 are crossed. To this 80 end the two gripper arms of each wire applying mechanism are journaled on spaced apart pins 76 carried by a head or support 77 which is preferably in the form of a rotatable yoke. The pivoted ends of the arms 85 are provided with arcuate gear segments 78 that mesh with the racks 79 carried upon and preferably integrally formed with a reciprocable rod 80. When the arms are to be adjusted from the uncrossed position illustrated in Fig. 7 to the crossed position illustrated in Fig. 9, to interchange the positions of the grippers with respect to support 77, the rod 80 is moved inwardly and when the arms are to be uncrossed, said rod is moved 90 outwardly. As the arms are being crossed, the angular ends thereof contact with the skirt of the cap 5 in the region where the wire is initially crossed so that the cap skirt is depressed at this place against the bottle 95 neck. By this means, the cap skirt is prevented from bunching where the wire is crossed and sufficient clearance is afforded between the wire where crossed and the cap skirt to permit the twisting of the wire to 100 come close against the cap skirt as illustrated in Fig. 10. Means for moving the rod 80 of each wire applying mechanism is inclusive of a fixed cam 81 having a cam groove receiving a roller 82 upon one end of an arm 83. The other end of this arm is coupled with a shaft 84 through the intermediation of an angular extension 85 provided upon the arm, a rod 86 passing through this angular extension, a spring 87 surrounding the rod and bearing at one end against a nut 88 on the rod, and an arm 89 fixed upon the shaft 84 and pressed upon by the other end of the spring 87. A square shaft 90 is received and slidable within a sleeve 91 having a square bore and carried upon the upper end of the extension 92 of the shaft 84. An arm 93 is fixed, at one end, upon the upper end of shaft 90 and carries a pin 94 at its other end. This pin 94 is received within an annular groove 95 formed in a collar 96 that is secured upon the corresponding rod 80. The shafts 84 pertaining to the various wire applying mechanisms on the machine are journaled in the bearing 110 115 120 125 130

support 28 to turn with respect thereto and to travel therewith. The cam 81 being stationary, the rods 80 of the various wire applying mechanisms are lineally moved at proper intervals to cross and uncross the gripper arms 45.

The gripper arms which have been crossed to draw the loop tightly against and almost completely about the bottle neck, as indicated in Fig. 9, are together turned to twist the wire whereafter these arms are uncrossed. The mechanism for turning each pair of gripper arms is inclusive of the head or support 77, the sleeve extension 94 in which 10 sleeve extension the corresponding rod 80 is slideable, the roller bearing 98 in which said sleeve extension is journaled, this roller bearing being mounted upon the support 30, the mutilated bevel pinion 99 fixed upon said 15 sleeve extension and employed to turn such extension to turn the corresponding gripper arms at the proper time, the arcuate or segmental rack 100 upon the normally stationary gear carrier 66, the disc 101 also fixed 20 upon said sleeve extension 97 and located alongside of said pinion 99, and the segmental arcuate track 102 located in a different circle from the circle that contains the rack 100, these circles being coaxial. When 25 the support 30 has been turned sufficiently to complete the crossing of the jaws, the pinion 99 that is to be operated in the cycle of operations being described, engages the rack 100 whereby the corresponding head 77 is 30 turned to turn the gripper arms to twist the wire as indicated in Fig. 10. When the gripper arms have been turned twice, the flattened edge of the disc 101 is brought into 35 engagement with the track 102 to prevent the pinion 99 from being further turned in order to arrest further rotation of said 40 arms.

In Fig. 13, rack 100 is not illustrated in the position it actually occupies in Fig. 8 but is so shown for sake of illustration, Fig. 13 being correct in this respect if it is not coupled with Fig. 8. In Fig. 13, the pinion 99 is entering upon its revolution.

The twisting revolutions of the gripper arms are concluded shortly after the first half of the cycle of operations being described has been completed. During the succeeding few degrees of turning movement of the support 30, the arms, which are not now being revolved, are uncrossed by the outward movement of the corresponding rod 80, a result which is due to the coaction of the cam elements 81 and 82 which control said rod in the manner hitherto described. 50 By the time the support 30 has completed three-quarters of its revolution, the bottle having the cap secured thereto by the twisted wire is lowered, the corresponding cam roller 55 then riding down on the cam track 20.

During the remaining quarter of the revolution of the support 30, the fully capped bottle is discharged from the table 10 by the star wheel 103, this star wheel serving to transfer the bottle to a chute 104 which returns the bottle to the table 2 from where 65 it can be removed by an attendant.

The table 10 with its section 9 are preferably rotated to bring the bottle to the various stations at which the wire is fed, cut, twisted and released from the grippers or 75 holders; but the invention is not to be limited to the direction of travel of the bottles and the table members 9 to the various stations where the wire is operated upon in the manner described.

While the machine herein disclosed includes a bottle positioning table member which travels with respect to a point in space to bring the bottle to various stations where the various operations may be performed, it is obvious that the invention involves the travel of the bottles relative to the mechanisms that perform the various operations, whether the bottles travel with 80 respect to a point in space or said mechanisms so travel.

Changes may be made without departing from the invention.

Having thus described my invention, I 95 claim:

1. The combination with two strand holders having arms upon which the holders are carried; of a support upon which said arms are pivoted to enable interchange in the positions of the holders with reference to the support; gears upon and coaxial with said arms; and a reciprocable rack member meshing with said gears to interchange the positions of the holders with reference to 100 said support.

2. The combination with two strand holders having arms upon which the holders are carried; of a support upon which said arms are pivoted at spaced apart places to enable the arms to be crossed to interchange 110 the positions of the holders with reference to the support; gears upon and coaxial with said arms; and a reciprocable rack member meshing with said gears to interchange the positions of said holders with reference to 115 said support.

3. The combination with two strand holders; of a support upon which the holders are mounted and upon which the holders are relatively movable to interchangeable 120 positions with reference to the support; and a mounting on which said support is rotatable.

4. The combination with two strand holders having arms upon which the holders are carried; of a support carrying said arms and upon which said arms are relatively movable to interchange the positions of the 125

holders with reference to the support; and a mounting on which said support is rotatable.

5. The combination with two strand holders; of a support upon which the holders are mounted and upon which the holders are relatively movable to interchangeable positions with reference to the support; means assembled with said support for placing the holders in such interchanged positions; and a mounting on which said support is rotatable.

6. The combination with two strand holders having arms upon which the holders are carried; of a support carrying said arms and upon which said arms are relatively movable to interchange the positions of the holders with reference to the support; means assembled with said support for changing the relative positions of said arms; and a mounting on which said support is rotatable.

7. The combination with two strand holders having arms upon which the holders are carried; of a support upon which said arms are pivoted to enable interchange in the positions of the holders with reference to the support; gears upon and coaxial with said arms; a reciprocable rack member assembled with said support and meshing with said gears to interchange the positions of the holders with reference to said support; and a mounting on which said support is rotatable.

8. The combination with two strand holders having arms upon which the holders are carried; of a support upon which said arms are pivoted at spaced apart places to enable the arms to be crossed to interchange the positions of the holders with reference to the support; gears upon and coaxial with said arms; a reciprocable rack member assembled with said support and meshing with said gears to interchange the positions of said holders with reference to said support; and a mounting on which said support is rotatable.

9. The combination with two strand holders; of a support upon which the holders are mounted and upon which the holders are relatively movable to interchangeable positions with reference to the support; a mounting on which said support is rotatable; a table member below and positioned to support an object in front of said holders to receive the strand therefrom; and mechanism for effecting relative vertical movement between said table member and support.

10. The combination with two strand holders having arms upon which the holders are carried; of a support carrying said arms and upon which said arms are relatively movable to interchange the positions of the holders with reference to the support; a mounting on which said support is rotatable; a table member below and positioned to support an object in front of said holders to receive the strand therefrom; and mechanism for effecting relative vertical movement between said table member and support.

ble; a table member below and positioned to support an object in front of said holders to receive the strand therefrom; and mechanism for effecting relative vertical movement between said table member and support.

11. The combination with two strand holders having arms upon which the holders are carried; of a support upon which said arms are pivoted to enable interchange in the positions of the holders with reference to the support; gears upon and coaxial with said arms; a reciprocable rack member assembled with said support and meshing with said gears to interchange the positions of the holders with reference to said support; a mounting on which said support is rotatable; a table member below and positioned to support an object in front of said holders to receive the strand therefrom; mechanism for effecting relative vertical movement between said table member and support; and mechanism in controlling relation to the holder adjusting means and the mechanism for effecting relative vertical movement between the table member and support and related to said means and mechanism to effect approaching relative vertical movement between the table member and support and interchange the positions of the holders in orderly sequence.

12. The combination with two strand holders having arms upon which the holders are carried; of a support upon which said arms are pivoted at spaced apart places to enable the arms to be crossed to interchange the positions of the holders with reference to the support; gears upon and coaxial with said arms; a reciprocable rack member assembled with said support and meshing with said gears to interchange the positions of said holders with reference to said support; a mounting on which said support is rotatable; a table member below and positioned to support an object in front of said holders to receive the strand therefrom; mechanism for effecting relative vertical movement between said table member and support; and mechanism in controlling relation to the holder adjusting means and the mechanism for effecting relative vertical movement between the table member and support and related to said means and mechanism to effect approaching relative vertical movement between the table member and support and interchange the positions of the holders in orderly sequence.

13. The combination with two strand holders; of a support upon which the holders are mounted and upon which the holders are relatively movable to interchangeable positions with reference to the support; means for interchanging the positions of the holders with reference to said support; a mounting on which said support is rotatable; a table member below and positioned to support an object in front of said holders to receive the strand therefrom; mechanism for effecting relative vertical movement between said table member and support; and mechanism in controlling relation to the holder adjusting means and the mechanism for effecting relative vertical movement between the table member and support and related to said means and mechanism to effect approaching relative vertical movement between the table member and support and interchange the positions of the holders in orderly sequence.

member below and positioned to support an object in front of said holders to receive the strand therefrom; mechanism for effecting relative vertical movement between said table member and support; and mechanism in controlling relation to the holder adjusting means and the mechanism for effecting relative vertical movement between the table member and support and related to said means and mechanism to effect approaching relative vertical movement between the table member and support and interchange the positions of the holders in orderly sequence. 70

14. The combination with two strand holders having arms upon which the holders are carried; of a support carrying said arms and upon which said arms are relatively movable to interchange the positions of the holders with reference to the support; means for moving said arms relatively to interchange the holders; a mounting on which said support is rotatable; a table member below and positioned to support an object in front of said holders to receive the strand therefrom; mechanism for effecting relative vertical movement between said table member and support; and mechanism in controlling relation to the holder adjusting means and the mechanism for effecting relative vertical movement between the table member and support and related to said means and mechanism to effect approaching relative vertical movement between the table member and support and interchange the positions of the holders in orderly sequence. 75

15. The combination with two strand holders having arms upon which the holders are carried; of a support upon which said arms are pivoted to enable interchange in the positions of the holders with reference to the support; means for turning said arms to interchange the holders; a mounting on which said support is rotatable; a table member below and positioned to support an object in front of said holders to receive the strand therefrom; mechanism for effecting relative vertical movement between said table member and support; and mechanism in controlling relation to the holder adjusting means and the mechanism for effecting relative vertical movement between the table member and support and related to said means and mechanism to effect approaching relative vertical movement between the table member and support and interchange the positions of the holders in orderly sequence. 80

16. The combination with two strand holders having arms upon which the holders are carried; of a support upon which said arms are pivoted at spaced apart places to enable the arms to be crossed to interchange the positions of the holders with reference to the support; means for turning the arms to interchange the holders; a mounting on which said support is rotatable; a table member below and positioned to support an object in front of said holders to receive the strand therefrom; mechanism for effecting relative vertical movement between said table member and support; means for feeding a strand to said holders; means for severing the strand portion fed to the holders; and mechanism in controlling relation to the holder adjusting means, the strand feeding means, the strand severing means, 85

below and positioned to support an object in front of said holders to receive the strand therefrom; mechanism for effecting relative vertical movement between said table member and support; and mechanism in controlling relation to the adjusting means and the mechanism for effecting relative vertical movement between the table member and support and related to said means and mechanism to effect approaching relative vertical movement between the table member and support and interchange the positions of the holders in orderly sequence. 90

17. The combination with two strand holders having arms upon which the holders are carried; of a support upon which said arms are pivoted to enable interchange in the positions of the holders with reference to the support; gears upon and coaxial with said arms; a reciprocable rack member assembled with said support and meshing with said gears to interchange the positions of the holders with reference to said support; a mounting on which said support is rotatable; a table member below and positioned to support an object in front of said holders to receive the strand therefrom; mechanism for effecting relative vertical movement between said table member and support; means for feeding a strand to said holders; means for severing the strand portion fed to the holders; and mechanism in controlling relation to the holder adjusting means, the strand feeding means, the strand severing means, and the mechanism for effecting relative vertical movement between the table member and support and related to all of said means and said mechanism to feed a strand portion to the holders, sever the fed strand portion, effect approaching relative vertical movement between the table member and support and interchange the positions of the holders in orderly sequence. 95

18. The combination with two strand holders having arms upon which the holders are carried; of a support upon which said arms are pivoted at spaced apart places to enable the arms to be crossed to interchange the positions of the holders with reference to the support; gears upon and coaxial with said arms; a reciprocable rack member assembled with said support and meshing with said gears to interchange the positions of said holders with reference to said support; a mounting on which said support is rotatable; a table member below and positioned to support an object in front of said holders to receive the strand therefrom; mechanism for effecting relative vertical movement between said table member and support; means for feeding a strand to said holders; means for severing the strand portion fed to the holders; and mechanism in controlling relation to the holder adjusting means, the strand feeding means, the strand severing means, 100

- and the mechanism for effecting relative vertical movement between the table member and support and related to all of said means and said mechanism to feed a strand portion to the holders, sever the fed strand portion, effect approaching relative vertical movement between the table member and support and interchange the positions of the holders in orderly sequence.
19. The combination with two strand holders; of a support upon which the holders are mounted and upon which the holders are relatively movable to interchangeable positions with reference to the support; a mounting on which said support is rotatable; a table member below and positioned to support an object in front of said holders to receive the strand therefrom; mechanism for effecting relative vertical movement between said table member and support; means for feeding a strand to said holders; means for severing the strand portion fed to the holders; and mechanism in controlling relation to the holder adjusting means, the strand feeding means, the strand severing means, and the mechanism for effecting relative vertical movement between the table member and support and related to all of said means and said mechanism to feed a strand portion to the holders, sever the fed strand portion, effect approaching relative vertical movement between the table member and support and interchange the positions of the holders in orderly sequence. 85
20. The combination with two strand holders having arms upon which the holders are carried; of a support upon which said arms are pivoted at spaced apart places to enable the arms to be crossed to interchange the positions of the holders with reference to the support; a mounting on which said support is rotatable; a table member below and positioned to support an object in front of said holders to receive the strand therefrom; mechanism for effecting relative vertical movement between said table member and support; means for feeding a strand to said holders; means for severing the strand portion fed to the holders; and mechanism in controlling relation to the holder adjusting means, the strand feeding means, the strand severing means, and the mechanism for effecting relative vertical movement between the table member and support and related to all of said means and said mechanism to feed a strand portion to the holders, sever the fed strand portion, effect approaching relative vertical movement between the table member and support and interchange the positions of the holders in orderly sequence. 90
21. The combination with two strand holders having arms upon which the holders are carried; of a support carrying said arms and upon which said arms are relatively movable to interchange the positions of the holders with reference to the support; a mounting on which said support is rotatable; a table member below and positioned to support an object in front of said holders to receive the strand therefrom; mechanism for effecting relative vertical movement between said table member and support; means for feeding a strand to said holders; means for severing the strand portion fed to the holders; and mechanism in controlling relation to the holder adjusting means, the strand feeding means, the strand severing means, and the mechanism for effecting relative vertical movement between the table member and support and related to all of said means and said mechanism to feed a strand portion to the holders, sever the fed strand portion, effect approaching relative vertical movement between the table member and support and interchange the positions of the holders in orderly sequence. 100
22. The combination with two strand holders having arms upon which the holders are carried; of a support upon which said arms are pivoted to enable interchange in the positions of the holders with reference to the support; a mounting on which said support is rotatable; a table member below and positioned to support an object in front of said holders to receive the strand therefrom; mechanism for effecting relative vertical movement between said table member and support; means for feeding a strand to said holders; means for severing the strand portion fed to the holders; and mechanism in controlling relation to the holder adjusting means, the strand feeding means, the strand severing means, and the mechanism for effecting relative vertical movement between the table member and support and related to all of said means and said mechanism to feed a strand portion to the holders, sever the fed strand portion, effect approaching relative vertical movement between the table member and support and interchange the positions of the holders in orderly sequence. 105
23. The combination with two strand holders; of a support upon which the holders are mounted and upon which the holders are relatively movable to interchangeable positions with reference to the support; and a strand receiving loop forming guide in front of said holders. 115
24. The combination with two strand holders; of a support upon which the holders are mounted and upon which the holders are relatively movable to interchangeable positions with reference to the support; a strand receiving loop forming guide in front of said holders; and a table member vertically below the interior of said guide, said support and table member being relatively movable vertically. 120
25. The combination with two strand holders; of a rotatable support upon which the 130

holders are mounted and upon which the holders are relatively movable to interchangeable positions with reference to the support; and a strand receiving loop forming guide in front of said holders.

26. The combination with two strand holders; of a rotatable support upon which the holders are mounted and upon which the holders are relatively movable to interchangeable positions with reference to the support; a strand receiving loop forming guide in front of said holders; and a table member vertically below the interior of said guide, said support and table member being relatively movable vertically.

27. The combination with two strand holders; of a rotatable support upon which the holders are mounted and upon which the holders are relatively movable to interchangeable positions with reference to the support; a strand receiving loop forming guide in front of said holders; a table member vertically below the interior of said guide, said support and table member being relatively movable vertically; and mechanism for feeding a strand into said holders and guide, elevating said table member, and turning said support.

28. The combination with two strand holders; of a rotatable support upon which the holders are mounted and upon which the holders are relatively movable to interchangeable positions with reference to the support; a strand receiving loop forming guide in front of said holders; a strand cutter for severing the strand portion held by the holders; a table member vertically below the interior of said guide, said support and table member being relatively movable vertically; and mechanism for feeding a strand into said holders and guide, operating the cutter to sever said strand portion, elevating said table member, and turning said support.

29. The combination with two strand holders; of a rotatable support upon which the holders are mounted and upon which the holders are relatively movable to interchangeable positions with reference to the support; and a table member, said support and table member being relatively movable vertically.

30. The combination with two strand holders; of a rotatable support upon which the holders are mounted and upon which the holders are relatively movable to interchangeable positions with reference to the support; a table member, said support and table member being relatively movable vertically; and mechanism for feeding a strand into said holders, elevating said table member, and turning said support.

31. The combination with two strand holders; of a rotatable support upon which

the holders are mounted and upon which the holders are relatively movable to interchangeable positions with reference to the support; a strand cutter for severing the strand portion held by the holders; a table member, said support and table member being relatively movable vertically; and mechanism for feeding a strand portion into said holders, operating the cutter to sever said strand portion, elevating said table member, and turning said support.

32. The combination with two strand holders; of a support upon which the holders are mounted and upon which the holders are relatively movable to interchangeable positions with reference to the support; a mounting on which said support is rotatable; a table member below and positioned to support an object in front of said holders to receive the strand therefrom; mechanism for effecting relative vertical movement between said table member and support; and mechanism for interchanging the positions of the holders, said mechanisms being spaced apart and which said support and table member being movable relatively thereto.

33. The combination with two strand holders; of a support upon which the holders are mounted and upon which the holders are relatively movable to interchangeable positions with reference to the support; a mounting on which said support is rotatable; a table member below and positioned to support an object in front of said holders to receive the strand therefrom; mechanism for effecting relative vertical movement between said table member and support; mechanism for feeding a strand to said holders; and mechanism for interchanging the positions of the holders, said mechanisms being spaced apart and said support and table member being movable relatively thereto.

34. The combination with two strand holders; of a support upon which the holders are mounted and upon which the holders are relatively movable to interchangeable positions with reference to the support; a mounting on which said support is rotatable; a table member below and positioned to support an object in front of said holders to receive the strand therefrom; mechanism for effecting relative vertical movement between said table member and support; mechanism for severing the strand; and mechanism for interchanging the positions of the holders, said mechanisms being spaced apart and said support and table member being movable relatively thereto.

35. The combination with two strand holders; of a support upon which the holders are mounted and upon which the holders are relatively movable to interchangeable positions with reference to the support; a mount-

ing on which said support is rotatable; a table member below and positioned to support an object in front of said holders to receive the strand therefrom; mechanism for effecting relative vertical movement between said table member and support; mechanism for interchanging the positions of the holders; and mechanism for turning said support to twist the strand held by said holders, 10 said mechanisms being spaced apart and said support and table member being movable relatively thereto.

36. The combination with two strand holders; of a support upon which the holders are mounted and upon which the holders are relatively movable to interchangeable positions with reference to the support; a mounting on which said support is rotatable; a table member below and positioned 15 to support an object in front of said holders to receive the strand therefrom; mechanism for effecting relative vertical movement between said table member and support; mechanism for feeding a strand to said holders; 20 mechanism for interchanging the positions of the holders; and mechanism for turning said support to twist the strand held by said holders, said mechanisms being spaced apart and said support and table member being 25 movable relatively thereto.

37. The combination with two strand holders; of a support upon which the holders are mounted and upon which the holders are relatively movable to interchangeable 30 positions with reference to the support; a mounting on which said support is rotatable; a table member below and positioned to support an object in front of said holders to receive the strand therefrom; mechanism 35 for effecting relative vertical movement between said table member and support; mechanism for feeding a strand to said holders; mechanism for severing the strand; mechanism for interchanging the positions of the 40 holders; and mechanism for turning said support to twist the strand held by said holders, said mechanism being spaced apart and said support and table member being 45 movable relatively thereto.

50 38. The combination with two strand holders; of a support upon which the holders are mounted and upon which the holders are relatively movable to interchangeable 55 positions with reference to the support; a mounting on which said support is rotatable; a table member below and positioned to support an object in front of said holders to receive the strand therefrom; mechanism 60 for effecting relative vertical movement between said table member and support; mechanism for interchanging the positions of the holders; mechanism for turning said support to twist the strand held by said 65 holders; and mechanism for relatively moving the holders to their initial relative positions.

tions; said mechanisms being spaced apart and said support and table member being movable relatively thereto.

39. The combination with two strand 70 holders; of a support upon which the holders are mounted and upon which the holders are relatively movable to interchangeable positions with reference to the support; a mounting on which said support is rotatable; a table member below and positioned to support an object in front of said holders to receive the strand therefrom; mechanism for effecting relative vertical movement 75 between said table member and support; mechanism for feeding a strand to said holders; mechanism for interchanging the positions of the holders; mechanism for turning said support to twist the strand held by said 80 holders; and mechanism for relatively moving the holders to their initial relative positions, said mechanisms being spaced apart and said support and table member being movable relatively thereto.

40. The combination with two strand 85 holders; of a support upon which the holders are mounted and upon which the holders are relatively movable to interchangeable 90 positions with reference to the support; a mounting on which said support is rotatable; a table member below and positioned to support an object in front of said holders to receive the strand therefrom; mechanism for effecting relative vertical movement 95 between said table member and support; mechanism for feeding a strand to said holders; mechanism for severing the strand; mechanism for interchanging the positions of the 100 holders; mechanism for turning said support to twist the strand held by said holders; and mechanism for relatively moving the 105 holders to their initial relative positions, said mechanisms being spaced apart and said support and table member being movable relatively thereto.

41. The combination with two strand 110 holders; of a support upon which the holders are mounted and upon which the holders are relatively movable to interchangeable 115 positions with reference to the support; a mounting on which said support is rotatable; a table member below and positioned to support an object in front of said holders to receive the strand therefrom; mechanism for effecting relative vertical movement 120 between said table member and support; mechanism for interchanging the positions of the holders; mechanism for turning said support to twist the strand held by said holders; mechanism for relatively moving the 125 holders to their initial relative positions; and mechanism for restoring the table member to its initial position, said mechanisms being spaced apart and said support and table member being movable relatively thereto.

42. The combination with two strand 130

holders; of a support upon which the holders are mounted and upon which the holders are relatively movable to interchangeable positions with reference to the support; a mounting on which said support is rotatable; a table member below and positioned to support an object in front of said holders to receive the strand therefrom; mechanism for effecting relative vertical movement between said table member and support; mechanism for feeding a strand to said holders; mechanism for interchanging the positions of the holders; mechanism for turning said support to twist the strand held by said holders; mechanism for relatively moving the holders to their initial relative positions; and mechanism for restoring the table member to its initial position, said mechanisms being spaced apart and said support and table member being movable relatively thereto.

43. The combination with two strand holders; of a support upon which the holders are mounted and upon which the holders are relatively movable to interchangeable positions with reference to the support; a mounting on which said support is rotatable; a table member below and positioned to support an object in front of said holders to receive the strand therefrom; mechanism for effecting relative vertical movement between said table member and support; mechanism for feeding a strand to said holders; mechanism for severing the strand; mechanism for interchanging the positions of the holders; mechanism for turning said support to twist the strand held by said holders; mechanism for relatively moving the holders to their initial relative positions; and mechanism for restoring the table member to its initial position, said mechanisms being spaced apart and said support and table member being movable relatively thereto.

44. The combination with a table member for a bottle having a skirted closure cap thereon; of mechanism for forming a strand into a loop whose plane is angular to the axis of the bottle on the table member and positioning said loop in line with the neck of the bottle, said mechanism and table member being relatively adjustable along

the bottle axes to enable the location of the loop about the skirt of the closure cap; means for severing the portion of the strand 55 that is shaped into loop form; and mechanism for twisting the loop ends together to form the loop into a ring and contract the ring about the skirt of the cap.

45. The combination with a table member 60 for a bottle having a skirted closure cap thereon; of a strand receiving loop forming guide above the table member and whose plane is angular to the axis of the bottle on the table member, said guide and table member being relatively adjustable along the bottle axis to enable the location of the cap skirt in the loop formed by said loop forming guide; and mechanism for twisting the ends of the loop together to form the loop 70 into a cap skirt contracting ring.

46. The combination with a table member 75 for a bottle having a skirted closure cap thereon; of mechanism for shaping a portion of a strand into loop form, said table member and mechanism being relatively adjustable along the bottle axis to enable the location of the loop about the skirt of the closure cap; mechanism for severing the portion of the strand that is shaped into loop 80 form; and mechanism for twisting the ends of the loop together to form the loop into a cap skirt contracting ring, said mechanisms being spaced apart and said table member being in traveling relation thereto. 85

47. The combination with a table member 90 for a bottle having a skirted closure cap thereon; of mechanism for shaping a portion of a strand into loop form, said table member and mechanism being relatively adjustable along the bottle axis to enable the location of the loop about the skirt of the closure cap; mechanism for severing the portion of the strand that is shaped into loop 95 form; and mechanism for twisting the ends of the loop together to form the loop into a cap skirt contracting ring, some of said mechanisms being spaced apart and said table member being in traveling relation thereto. 100

In witness whereof, I hereunto subscribe my name.

OLOF N. TEVANDER.
